(57) **CLAIM**

The ornamental design for a washbasin, as shown and described.

DESCRIPTION

FIG. 1 is a perspective view of a first embodiment of a washbasin.

FIG. 2 is a top plan view thereof.

FIG. 3 is a bottom plan view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is a cross-sectional view taken along the line 8-8 in FIG. 4; and,

FIG. 9 is a cross-sectional view taken along the line 9-9 in FIG. 2.

The dark portions in cross-sectional FIGS. 8 and 9 form no part of the claimed design.

1 Claim, 9 Drawing Sheets
